UNITED STATES PATENT OFFICE.

EDWARD F. JOHNSON, OF PITTSFIELD, MASSACHUSETTS.

VALVE.

1,131,382.

Specification of Letters Patent.

Patented Mar. 9, 1915.

Application filed December 14, 1912. Serial No. 736,860.

To all whom it may concern:

Be it known that I, EDWARD F. JOHNSON, a citizen of the United States, residing at Pittsfield, in the county of Berkshire and State of Massachusetts, have invented certain new and useful Improvements in Valves, of which the following is a specification, reference being had therein to the accompanying drawing.

10 This invention relates to means adapted to be attached to an engine for a motor vehicle such as an automobile, and has for its object the production of a simple and efficient locking means for a valve whereby the 15 passage of gas may be conveniently cut off from the carburetor to the engine.

Another object of this invention is the production of a simple and efficient valve and lock therefor whereby the passage from 20 the carburetor to the cylinder of the explosive engine will be closed to prevent unauthorized parties from running the engine.

With these and other objects in view, this 25 invention consists of certain novel constructions, combinations and arrangements of parts as will be hereinafter fully described and claimed.

In the drawings:—Figure 1 is a sectional view through the hood of an automobile 30 showing the engine in side elevation and the present invention applied thereto. Fig. 2 is a detailed perspective of the valve and locking mechanism therefor. Fig. 3 is a central vertical section through the valve 35 casing. Fig. 4 is a side elevation of the valve casing showing the locking means attached thereto. Fig. 5 is a detail perspective of a modified form of the locking means which may be employed in connection with the 40 present valve mechanism. Fig. 6 is a vertical section through the collar carrying the spring pressed plunger taken at right angles to the showing in Fig. 3.

By referring to the drawings by numerals 45 it will be seen that 1 designates the body of the automobile in which is placed the usual explosive engine or engines 2 being connected to a gas supply pipe 3 by means of the usual Y-connection 4. A carburetor 5 50 is also carried adjacent the engine 2 and is operated in the usual manner; and between the carburetor 5 and the Y-supply pipe 4 is placed the valve casing 6. This valve casing 6 comprises a tubular body portion 7 to 55 which are connected the usual connecting means between the engine and carburetor

and this tubular body 7 is provided upon one side with a trunnion 8 in which is journaled one end of the valve supporting shaft 9.

An auxiliary casing 10 is attached to the body 7 of the valve casing 6 and comprises a securing plate 11 which is secured to the body 7 by means of the bolts or screws 12. The auxiliary casing 10 is provided with a centrally arranged aperture 13 through which passes the valve supporting shaft 9, and a gate valve 14 is secured to the shaft 9 by means of a securing screw 15. This shaft 9 is provided with a notched portion 16 intermediate its ends and this notched portion 16 is engaged by means of a plunger 17 carried within the collar 18 of the auxiliary casing 10. The collar 18 is provided with a centrally arranged aperture 19 and around 75 the plunger 17 is placed a coil spring 20 for normally holding the plunger 17 in engagement with the notched portion 16 of the shaft 9 and thereby hold the valve 14 in an open position. A threaded plug 21 seals the upper end of the collar 18. The plug 21 being obviously removable, access may be readily had to the spring 20 and plunger 17, when desired so repairs or replacements are facilitated. The plug 21 also forms an upper bearing surface for the spring 20, so that said spring is constantly exerting a tension tending to retain the plunger 17 in engagement with the notch 16 of the shaft 9, so that said shaft 9 is normally held in position to retain valve 14 open, as clearly shown in Fig. 3 of the accompanying drawings.

The auxiliary casing 10 is provided with an integral laterally extending arm 22 which arm terminates in a broad laterally extending supporting plate 23 being provided with an aperture 24. A locking plate 25 is secured to the outer end of the shaft 9 by means of a pin or set screw 26, and the forward end of the locking plate 25 is provided with a depending tongue 27 which is provided with an aperture 28 through which aperture is adapted to pass the hook 29 of the padlock 30.

From the foregoing description it will be 105 seen that as the lock 30 engages the tongue 27 the locking plate 25 will be firmly held in engagement with the plate 22 thereby holding the valve 14 in a closed position and preventing the passage of gas through the casing 7. It is to be understood of course, that the locking plate, or handle 25 is fast on the

outer end of the shaft 9, so that when the said handle is turned to place the same upon the supporting plate 22 the shaft 9 is rotated against the pressure of the spring 5 pressed plunger 17 causing the said plunger to ride out of the notch 16.

From the foregoing description it will be seen that when the valve is so locked unauthorized parties will not be able to use the 10 machine or engine thereby insuring safety to the engine while the owner or operator is compelled to leave the machine standing upon the street.

As illustrated in Fig. 5, there is shown an 15 embodiment of the invention wherein the supporting arm or plate 24 is provided with a pocket portion 31 which pocket portion has its upper edge flush with the top of the plate 25 whereby the edges of the plate 25 20 will be shielded and the lateral strain upon the plate 25 will be relieved from the depending tongue 27 which is adapted to be engaged by the lock 29.

Having thus described the invention, what 25 is claimed as new, is:—

1. A device of the character described comprising a tube, a casing carried thereby, a valve in the tube provided with a shaft that extends through the casing, means in 30 the casing for engaging the shaft to normally hold the valve open, a supporting arm projecting laterally from the casing and having a handle seat provided with an opening in its free end, a handle for rotating the shaft to close the valve, said handle adapted to lie on the seat of the support and having a tongue adapted to project through the 35 opening, and a lock for engaging the tongue.

2. A device of the character described

comprising a tube, a casing carried thereby, 40 a valve in the tube and having a shaft journaled in and extending through the casing, a laterally projecting collar carried by the casing, said shaft having a notch formed therein, a plunger in the collar, a cap for 45 closing the upper end of said collar, a spring bearing on the plunger to force the plunger in engagement with the notch to cause the shaft to normally retain the valve open, a handle carried by the extended portion of 50 the shaft, a support carried by the casing, and means for locking the handle to the support to retain the valve closed.

3. A device of the class described comprising a tube, a disk valve mounted within 55 said tube and adapted to open and close a passage therethrough, a shaft for supporting said valve, a casing secured to said tube, said casing provided with a laterally projecting enlarged locking plate engaging 60 member provided with an upwardly extending flange extending therearound for constituting a pocket, a locking plate fixedly secured to said shaft and adapted to fit within said pocket formed for resisting the lateral 65 movement of said locking plate and adapted to hold said valve supporting shaft against longitudinal movement, and means carried by said locking plate for holding the same against accidental removal from said pocket.

In testimony whereof I hereunto affix my signature in presence of two witnesses:

EDWARD F. JOHNSON.
